COLLAPSIBLE FUEL TANK

Marion M. Cunningham and George P. McDowell,
South Bend, Ind., assignors to United States
Rubber Company, New York, N. Y., a corpora-
tion of New Jersey

Application January 16, 1945, Serial No. 573,128

10 Claims. (Cl. 244—135)

1

Our invention relates to liquid containers and more particularly to improvements in collapsible fuel tanks or cells.

In the manufacture and use of liquid containers, such as the fabricated fuel cells used as airplane tanks, difficulty is encountered in manufacturing the seams where the edges of the coated fabric are brought together. Another problem involved at the seams is the necessity for keeping the edges of the fabric away from the contents of the cell and to rely on the fabric coating for preventing capillary attraction or seepage through the fabric so that the exterior of the cell remains free from the cell contents. This is particularly important when the cells are used for transporting inflammable materials such as gasoline.

We overcome some of the foregoing difficulties by reducing the number of seams and providing a seam construction in which the edges of the fabric and coating at the seams extend externally of the cell. The seams are reinforced both internally and externally without materially impairing the collapsible characteristics of the cell.

Another difficulty encountered in the operation of such fuel cells is the manner of attachment of the cells to the supporting structures, such as airplane frames.

We have provided a quickly attachable and detachable means for securing such cells to the adjacent structural elements by the manipulation of handles or knobs extending inwardly of the cells. The handles or knobs may be reached through the normal service opening, if the cell be small, or by an operator positioned within the cell, if the cell be large.

The accompanying drawings illustrate certain present preferred forms of the invention in which:

Fig. 1 is an exploded view of the shapes of the several coated fabric elements before they are brought together;

Fig. 2 is a perspective view of the cell partially broken away, looking from the bottom;

Fig. 3 is a perspective view, looking down on the cell;

Fig. 4 is a view, similar to Fig. 1, of a modification of the invention;

Fig. 5 is a cross-sectional view of the cell mounted within a supporting structure of an airplane, the cell being cut along section line V—V of Fig. 3;

Fig. 6 is a transverse sectional view through the wing structure taken on line VI—VI of Fig. 5;

2

Fig. 7 is an enlarged detail view in section illustrating in detail one of the seams;

Fig. 8 is a corner view of the cell;

Fig. 9 is a cross-sectional enlargement of one of the fastening elements taken along the section line IX—IX of Fig. 5;

Fig. 10 is a cross-sectional view of another fastening element taken along the section line X—X of Fig. 6;

Fig. 11 is a detail view of a portion of the fastening element shown in Fig. 10;

Fig. 12 is a perspective view of a cell broken away to show a reinforcing frame in the bottom;

Fig. 13 is a perspective view of the frame removed from the cell;

Fig. 14 is a detail of a connection plug for the frame sections; and

Fig. 15 is a cross-section of the frame and attaching means taken on the line XV—XV of Fig. 12.

Referring particularly to Figs. 1 to 3, and Figs. 7 and 8, a liquid container or cell embodying our invention comprises a plurality of strips of coated fabric 1 and 2. The strip 1 is folded transversely to provide four surfaces of the cell, and the ends of the edges 3 and 4 are united by a seam 5. The strips 2 are united to strip 1 by seams 6 and 7.

As is particularly shown in Fig. 7, the fabric strips each comprises a layer of fabric 8 which is coated at least on its inner surface with a layer of plastic composition 9 which seals the fabric and is resistant to the contents of the cell. The fabric 8 is preferably a square woven fabric and the coating composition 9 may be of synthetic rubber or natural rubber having a further coating 10 of a material resistant to the cell contents. Variations in the fabric and the coating may be made as desired.

The seams 6 are formed exteriorly of the main body of the cell by having the faces of the contiguous coatings 9 and 10 extend outwardly of the cell in engagement with each other at the cell corner. These surfaces may be treated

with a bonding adhesive, to cause adhesion when the cell is cured, or they may be vulcanized directly together. Reinforcing stitching 11 is passed through the seams externally of the cell.

For adding stability to the cell and for closing any seam 6, a flange or angle piece 12 of natural rubber or synthetic rubber, depending on the nature of the cell contents, is placed within the cell behind the seam 6 and perma-

nently secured to the coating layer 10 during the cell curing or vulcanizing step.

In the manufacture of the cell, a destructible form is provided about which the strips 1 and 2 are shaped. Before shaping the strips 1 and 2, the angle pieces 12 are placed on the form at the corners thereof so that they are in position when the seams are completed. The seams 5 and 7 are of a similar construction.

Referring to Fig. 8, provision is made at some corners of the cell for admitting a sewing machine or a trimming machine by terminating the seam flanges before they meet and reinforcing the cell corner with a pad or cover 14. In this construction the seamed edges may be readily trimmed and sewed.

Our cell eliminates much of the labor and care heretofore involved in making lapped seams where auxiliary sealing means had to be applied over the edges of the fabric to prevent capillary attraction and in addition the seams of the present invention are stronger and more reliable. The seam flanges add a certain amount of stability to the cell without impairing its overall flexibility for the purpose of permitting it to be forced into an airplane structure or removed therefrom.

Referring to Fig. 4, there is shown a modified form of the invention, in which a single piece of fabric 14 is folded so as to eliminate the two seams necessary to join the top edges of the strips 2 of Fig. 1 to the strips 1.

On mounting such containers in their supporting structures they are frequently placed inside a metal container or casing 15 which is previously inserted in a cavity in a structural frame work 16 of the machine in which the cell is mounted. In the drawings, the structural frame work 16 is illustrated as a portion of the wing surface of an airplane and comprises a lower wing surface 17, a lower bracing section 18, an upper bracing section 19 and an upper wing surface 20. It is to be understood that the structure 16 may provide a plurality of cavities in which the casings 15, usually of different sizes and shapes, may be inserted.

For placing the cell in the casing 15 a section 21 of the bracing structure 18 is made removable to provide an opening which is ultimately covered by the metal of the wing surface 17. Above the removable section 21, the casing 15 is provided with a removable plate 22 which is secured to the remainder of the casing by screws 23 threaded in plates 24. The cell is provided with a service or manhole plate 25 which is secured to the cell by a suitable fitting 26, one form of which is shown in the Steiner Patent 2,326,263. When the lower wing surface 17 is removed, so that the access is had to the casing 15, the cell may be collapsed and inserted into or withdrawn from the casing 15. When the plate 25 is removed, access may be had to the interior of the cell. The size of the plate 25 depends upon the capacity of the cell. In the small cells the plate is made smaller as an operator working through the opening can reach substantially all parts of the interior of the cell. In the case of large cells the plate 25 and the fitting 26 may be made large enough to permit the operator to enter the cell.

The cell is also provided with one or more fittings 27 for the attachment of an outlet pipe, not shown, and a fitting 28 for the attachment of a vent, not shown.

For securing the cell walls to the frame work

10 16, we have provided quickly attachable and detachable securing means which can be manipulated from the interior of the cell either by an operator reaching through the opening in the fitting 26 or by entering the cell, as may be necessary. In either case, the operator can manipulate the fastening means from the interior of the cell into a cooperative engagement with complementary securing means attached to the frame 15 work 16 or the casing 15. These fastening means may vary in detail in accordance with their positions on the cell surfaces and the effect of the force of gravity thereon. In all cases, the fastening means are characterized by having knobs or handles 29 and 30 extending interiorly into the cell so that they can be readily grasped by the operator.

Referring particularly to Figs. 3, 5, 6, and 9, several of the fastening means 31 are disposed about the upper surface of the cell and each includes a handle 29 extending into the cell. Each handle 29 is provided with a pin 32 having a neck 33 and button 34. The neck 33 extends through a plate 35 from which spring fingers or a split ring 36 extend outwardly of the cell. A male button 37 is secured radially inwardly of the fingers 36 to provide a channel 38 for a wire C-ring 39. A covering 40 of a suitable plastic material such as synthetic rubber encases the outer part of the pin 32 and provides the gripping surface of the handle 29. The covering 40 is bonded to the pin 32 and the lower face of the plate 35. The coating 40 extends radially outwardly as a tapered disc or flange 41 which also overlaps a portion of the upper face of the plate 35 and terminates a distance from the split fingers 36 to permit the latter to have flexing movement. However, the coating 40 and the flange 41 seal the fastener fingers from the contents of the cell. The fabric 8 and the coating composition 9 are attached to the flange 41, but terminate a distance from the fastener 31 so that the material of the flange seals the fabric edge of the fabric 8 from the contents of the cell.

45 In alignment with the normal position of each of the handles 29 and the attached fingers 36 and button 37 there is provided an opening 42 in the casing 15. A plate 43 having a depending female spring button 44 internally carrying C-ring 39 is positioned over each opening 42 and a cap piece 45 is placed over each plate 43, and secured in position by rivets 46. The plate 43 is of less diameter than the inner diameter of the cap piece 45 so that the plate 43 is capable of considerable lateral adjustment in the opening 42 to permit limited adjustment of the position of the button 44. The button 44 is aligned to pass between the fingers 36 and the button 37 and to snap the ring 39 behind the head of the spring button 37. The construction just described provides a snap button construction by which the handle 29 may be quickly secured to the plate 43, or detached therefrom by an operator working from within the cell.

65 Referring to Figs. 5, 6, 10, and 11, each handle 30 comprises a pin 50 having an outer button 51, a neck 52, a flange 53, and a recess 54 for the reception of a plate 55. The flange 53 and the plate 55, as well as the inwardly extending end 70 of the pin 50, are covered by and bonded to a coating composition, such as synthetic rubber, terminating in a tapering flange to which the fabric 8 is attached in the manner set forth in the description of Fig. 9. The button 51 is adapted to sit in a bayonet slot 56 formed in the casing

45. A spring 57, secured to the casing 45, extends over the end of the pin 50 for holding the pin in position. The spring 57 is provided with a detent 58 for engaging a recess 59 at the end of the pin 50. With this construction an operator working from the inside of the cell can grasp the handle 30 and work the flange 51 through the upper enlarged portion of the slot 56 into its lower position where it is held by the weight of the adjacent cell wall and the spring 57. In order to release the fastening means, the handle 30 is raised against the friction of the spring 57 until the flange 51 can be withdrawn through the enlarged portion of the opening 56. If necessary, openings 58 may be provided in adjacent portions of the airplane structure to provide clearance for the springs 57.

In some cell structures, irregularities in the shape of the plane wings or cells of large sizes render it advisable to use a bracing device at the bottom of the cells in order to prevent shifting of portions of the cell walls relative to the plane structure, whereby the cell is normally held in extended position to substantially conform to the size of the opening in the plane.

In Figs. 12 to 15 we have shown such construction in which a frame 60 preferably comprising perforated pipe sections 61, 62, 63, and 64 are joined together by rubber plugs 65, 66, 67, and 68 which are inserted in the adjacent ends with the pipe sections. The frame is held in position by tabs 69 which are bonded to the corner strips 12 and the cell corners 13. Tapes 70 are secured to the tabs 69 as by stitching 71 to provide free ends which can be brought over the pipe sections and tied as shown at 72 in Figs. 12 and 15.

The perforations 73 in the pipe sections permit the cell contents to fill and escape therefrom so that the capacity of the cell is not materially reduced and there is no buoyant effect produced by the pipe sections.

In assembling the frame 60 in the cell the sections are first bent at either of the plugs 65, 67 or 66, 68, depending upon the size and shape of the cell, and then the collapsed frame inserted through the manhole. The frame 60 is next tied in the bottom of the cell, as illustrated in Figs. 12 and 15.

This construction has a further advantage in that it does not restrain the lower part of the tank with respect to the airplane structure so that a considerable amount of deformation of the cell may take place in a crash.

It will thus be seen that we have provided improvements in the construction of seams of such cells and in the means for fastening the cells to the supporting structure.

While we have shown and described certain preferred embodiments of our invention, it is to be understood that the invention may be otherwise modified within the spirit of the invention and the scope of the appended claims.

Having thus described our invention, what we claim and desire to protect by Letters Patent is:

1. A cell comprising a flexible wall and means for securing the wall to a supporting structure comprising an attaching element forming a unit with and extending outwardly of the cell, and manipulating means for the element extending inwardly of and secured to the cell for attaching and detaching said element from an individual mating element on the supporting structure.

2. A cell comprising a flexible wall and means for securing the wall to a supporting structure

comprising a button forming a unit with and extending outwardly of the cell, and manipulating means for the button extending inwardly of and secured to the cell for attaching and detaching said button from a corresponding individual mating element on the supporting structure.

3. A cell comprising a flexible wall and means for securing the wall to a supporting structure comprising a snap button forming a unit with 10 and extending outwardly of the cell, and manipulating means for the snap button extending inwardly of and secured to the cell for attaching and detaching said button from a complementary button on the supporting structure.

15 4. A cell comprising flexible walls of fabric and an inner coating composition therefor resistant to the contents of the cell, and means for securing the walls to a supporting structure comprising buttons extending outwardly of the cell through openings in the fabric, and manipulating means for the buttons extending inwardly of and secured to the cell and sealing the edges of the fabric at said openings from the cell contents.

25 5. A cell comprising a flexible wall and quickly operative means for securing the wall to a supporting structure comprising attaching elements forming a unit with and extending outwardly of the cell and a handle in alignment with each element extending inwardly of the cell for the separate actuation of the aligned element.

30 6. The combination with a supporting structure having fixed supporting elements, of a flexible cell provided with an entrance opening and having formed as a unitary part thereof outwardly extending supporting elements for cooperation with the elements on the structure and manipulating means secured to and extending inwardly of the cell in alignment with the elements on the cell, whereby an operator working through said entrance in the cell may selectively manipulate the elements on the cell into engagement with the elements on the structure.

35 7. The combination with a supporting structure having fixed supporting elements of a quickly attachable character, of a flexible cell provided with an entrance opening and having outwardly extending supporting elements of a quickly attachable character for cooperation with the elements on the structure, and manipulating means extending inwardly of and secured to the cell in alignment with the elements on the cell, whereby an operator working through said entrance in the cell may selectively manipulate the elements on the cell into engagement with the elements on the structure.

40 8. The combination with a cell enclosing structure having normally horizontal and vertical surfaces for enclosing a cell and fixed overhanging cell supporting elements and fixed laterally extending cell supporting elements fixed to said structure, both of which elements are of a quickly attachable character, of a cell composed of coated fabric having an entrance opening 45 therein, laterally extending attaching elements and upwardly extending attaching elements extending from said cell for cooperation with the elements on the structure, and handles extending inwardly of the cell and attached thereto in alignment with the outwardly extending elements, whereby an operator working the handles through the opening in the cell may separately actuate the elements on the cell into engagement with the elements on the structure.

45 9. A cell comprising a flexible wall, a support-

ing structure for said wall having an opening therein provided with an enlarged portion and a narrower extremity, an attaching head affixed to said flexible wall, said head being smaller than said enlarged portion but larger than said narrower extremity of said opening, a groove at the base of said head adapted to receive the edges of the narrower extremity of said opening, and manipulating means for said head extending inwardly of said cell and secured to said wall.

10. A cell comprising a flexible wall, a supporting structure for said wall having an opening therein provided with an enlarged portion and a narrower extremity, an attaching head fixed to said flexible wall, said head being smaller than said enlarged portion but larger than said narrower extremity of said opening, a groove at the base of said head adapted to receive the edges of the narrower extremity of said opening, manipu-

lating means for said head extending inwardly of said cell and secured to said wall, and a spring attached to said supporting structure and adapted to act on said head to hold same in said narrower extremity.
